LOUIS B. GIRARD, OF LOS ANGELES, CALIFORNIA, ASSIGNOR, BY MESNE ASSIGNMENTS, TO JOHN P. WHITMORE, OF SOUTH PASADENA, CALIFORNIA, AND LOUIS B. GIRARD, OF LOS ANGELES, CALIFORNIA.

WINDOW-SHADE MOUNTER.

1,318,321.

Specification of Letters Patent.

Patented Oct. 7, 1919.

Application filed October 2, 1916. Serial No. 123,436.

To all whom it may concern:

Be it known that I, LOUIS B. GIRARD, a citizen of the United States, residing at Los Angeles, in the county of Los Angeles and State of California, have invented a new and useful Window-Shade Mounter, of which the following is a specification.

This invention relates to means for mounting window shades on their rollers, and the main object of the invention is to provide a machine whereby the fastening of the shade on the roller may be effected quickly, easily and with great accuracy and security.

Another object of the invention is to provide improved die mechanism for forming and driving fasteners for shades or for other articles.

The accompanying drawings illustrate means embodying my invention and referring thereto.

Figure 1 is a plan view of the machine.

Fig. 1^a is a section on line a—a in Fig. 1.

Fig. 2 is an end view thereof, taken from the left hand of Fig. 1.

Fig. 3 is an end view taken from the right hand of Fig. 1.

Fig. 4 is a side elevation of the die means, the die head being shown in section and the dies being shown in normal or unoperated position.

Fig. 5 is a view similar to Fig. 4, the dies being shown in partially operated position.

Fig. 6 is a horizontal section on line 6—6 in Fig. 4, showing the staple strip in position for cutting the staple.

Fig. 7 is a section on line 7—7 in Fig. 4.

Fig. 8 is a section on line 8—8 in Fig. 5.

Fig. 9 is a section on line 9—9 in Fig. 1, the dies being shown in fully operated position.

Fig. 10 is a partial elevation on the reverse side from Fig. 9, showing the spring means for advancing the stock strip.

Fig. 11 is a partial vertical section of the roller supporting means.

Fig. 12 is a vertical section of the chuck for rotating the roller.

Fig. 13 is a vertical section of the pick up for the roller.

Fig. 14 is a plan view and Fig. 15 a side elevation of the staple strip after formation of the prongs thereon and before cutting off.

Fig. 16 is a plan view, Fig. 17 a side elevation and Fig. 18 a front elevation of the staple formed by the machine.

55

Fig. 19 is a section on line 19—19 in Fig. 9.

Fig. 20 is a section on line 20—20 in Fig. 9.

Fig. 21 is a side elevation of a modified form of the means for varying the height of the roller support.

60

Fig. 22 is a section through the adjusting lever for the roller support, showing a modified form of the means for fixing the position of the same.

65

The working parts of the machine are preferably mounted in a suitable frame comprising a base or table 1, and standards 2 and 3 mounted thereon. Standards 2 and 3 may be provided with forward extensions 4 and 5 from their lower parts, serving to support brackets 6 and 7 which are mounted on the respective extensions 4 and 5, so as to be adjustable to or from the standards 2 and 3, said brackets for example, being slidable on parts 4 and 5 and being clamped thereto by cap screws 8, passing through slots 9 in said brackets.

70

A shaft 11, herein called the pick up shaft, extends through bearings 12 and 13 on the respective brackets 6 and 7, and is provided with an operating arm or handle 15 mounted on a sleeve 16 which is mounted on shaft 11 by a key or spline 17 engaging in a longitudinal groove 11', in said shaft, and is provided with an arm 18 having at its rear end, a pick up or roller engaging device 19, formed preferably as a head on a spindle 20 mounted to turn in a bearing 21 on arm 18, said head having a conical socket or recess 19' adapted to receive the pin at one end 90 of the shade roller.

75

A driving chuck 22 is provided for engaging the other end of the roller, said chuck being mounted on a mandrel 23, mounted to turn in bearings 24 and 24' on a chuck carrier 25, which is mounted on pick up shaft 11 so as to turn therewith. A rubber friction ring 22' is secured in chuck 22 to engage the end of the shade roller. Bearing 24' is preferably provided with an end 95 thrust ball bearing 26 for the chuck 22.

95

A pulley 27 is fastened to mandrel 23 and is provided with a groove 27' for receiving a round belt 28, which passes over a pulley 100.

30 on the shaft 31 of a motor 32, which may be an electric motor, belt 28 being loose and therefore inoperative when the parts are in normal position. Pulley 30 is preferably 5 provided with wide flanges 30' to retain the belt thereon when slack. A guard 33 is provided for pulley 27, being formed for example as a half ring flange on a cross arm 34 having a hub 34' adjustably mounted 10 on an extension 35 of bearing 24, by means of a set screw 36.

Two bars 38 and 38' formed for example as angle irons, are mounted on bed or table 1, to form a guide or way for a roller support or bed member 39, which is formed 15 preferably of channel iron with the flanges 39' thereof extending upwardly so as to form guards for the roller, whereby the roller is retained in proper position, as indicated in Fig. 9. Said member 39 is mounted on suitable means for adjusting it vertically, being provided for example with wedges 40 secured to the bottom thereof and adapted to slide on studs 41 extending between and secured to the bars 38 and 38', so that by longitudinal movement of the member 39 it may be caused to move vertically, and thereby raise and lower the roller to bring it to proper position with 25 relation to the stapling means. Such longitudinal movement of the member 39 may be effected by a lever 44, pivoted at 45 to the base of standard 3 and connected to member 39 by a pin 46 on member 39 engaging 30 in a slot 47 in lever 44. Said lever is also provided with a slot 48 adapted to engage any one of a number of studs 49 which are mounted on a segment 50 carried by the bracket 7, said segment being provided with 35 holes 52 to receive said studs so as to provide for shifting of said studs when required for odd sizes, it being understood that the position of the studs on segment 50 corresponds to the different adjustments 40 of lever 44 for the standard sizes of roller. Lever 44 is mounted with sufficient flexibility to permit it to be forced over any one of the studs in changing its adjustment.

A shaft 54 is mounted in the standards 50 2 and 3 so as to be held in fixed position at the rear of the roller supporting means and a die mechanism for forming and driving staples is mounted on said shaft so as to be movable longitudinally and vertically, said mechanism being carried by an arm 55 having its hub 55' clamped on a sleeve 53 mounted to turn on shaft 54 and having a key 56 engaged in a longitudinal groove or key way 57 in said shaft, said groove being 55 of sufficiently greater width than the key 56 to permit of limited rotative movement of the arm 55 on the shaft, said arm 55 is also provided with a projection, preferably formed as a screw 60 adjustably mounted 60 thereon and adapted to engage a suitable

fixed stop, such as bar 61, on table 1, at the spring containing end of the roller to arrest the downward movement of the die means as hereinafter described.

A die head 58 is mounted rigidly on the 70 arm 55, and is provided with a vertical way 63, with a side plate 64 closing said way at one side, and with a removable bottom plate 65 which constitutes the female die, being formed with an aperture or die hole 66, 75 whose rear wall 66' conforms to the shape of the rear and front edges of the staple or fastener to be cut. The front wall 67 of the hole 66 is formed with a notch or recess 68 to receive the point at the forward end 80 of the staple strip. Plate 65 is also formed with a channel or way 69 formed for example in a removable or replaceable die member 73 for receiving and guiding the staple strip, the portion of the plate directly at the rear of the cutting edge or wall 66' inclining slightly downward from the bottom of said channel and forming a continuation thereof, and being somewhat below the top of the front wall 67 of hole 90 66, so that the staple strip fed forward through channel 69 will be arrested by its forward end striking said front wall. A cutting and forming punch or male die 70 is mounted to slide vertically in way 63 and 95 a severing, forming and driving punch or male die 71 is mounted to slide in a vertical slot or way 72 in punch 70. The bottoms of the respective punches 70 and 71 are concavely curved as shown at 70' and 71', 100 to approximately conform to the cylindrical surface of the shade roller, and the bottom of the fixed die plate 65 is also similarly curved as shown at 65'.

The die means aforesaid are operated by 105 a lever 75, pivoted at 76 to arm 55 and provided with a handle 77. A pair of links 78 are pivoted at 79 to said lever and at 80 to a bell crank 81 which is pivoted at 83 to arm 55 and at 84 to a pair of links 85 110 whose lower ends are pivoted at 86 to a lever 87 which is pivotally mounted at 88 on a stud 89, and is connected to the main cutting and forming punch 70 by a pair of links 90, pivoted at their upper ends by 115 pivot 91 to lever 87 and at their lower ends by pivot 92 to an ear 93 on the upper end of punch 70. Stud 89 is vertically adjustable on arm 55 being formed for example as a bolt passing through a vertical slot 94 in 120 said arm and fastened by its nut 95. The supplementary punch 71 is connected directly to lever 75 by a pair of links 96 pivoted at 97 and 98 respectively to the lever and to an ear 99 on the upper end of 125 said punch.

The staple strip, indicated at 100, is wound on a reel 101, which is rotatably mounted on a shaft 102 on arm 104 extending rigidly from the hub 55' which carries 120

arm 55, the arms 55 and 104 constituting in effect a single cross arm. Said reel is engaged by a tension spring 105 mounted on arm 104 and adjusted by means of a screw, 5 to give the required tension for the feed. The outer end of the strip 100 is passed under a guiding pin 111, through a gripping device on a feeding lever 108 pivoted at 109 to arm 55 and then through a gripping device 10 on a retaining device 110 fixed on arm 55. Lever 108 is operated by a projection 112 thereof which is engaged by the operating lever 75 at a certain part of its stroke, to swing the lever 108 to the rear, 15 and a spring 113 is connected to said lever 108 and to arm 55 to return said lever to normal position. The gripping device on lever 108 may comprise a jaw 114 formed with a channel 115 through which the strip 20 100 passes, and a pawl 116 pivoted at 117 to said lever and forced into engagement with the strip by a spring 118. The retaining device 110 is formed as a jaw similar to jaw 114 and co-operates with a pawl 121 25 similar to pawl 116 and operated by a spring 122.

A shade supporting platform 125 is provided on table 1, inclining upwardly and forwardly to about the level of the top 30 of the shade roller support 39. A gage bar 126 is also provided on table 1, extending rearwardly from the roller support to form a side gage for the pile of shades on the table.

35 While any suitable form of die means may be used with the above described mounting apparatus I prefer to use the form shown in the drawing which is adapted to form and drive a fastener from a plain strip of 40 metal at each feeding operation of the strip, and which reduces to a minimum the amount of material required for each staple or fastener. In this construction the female member of the die means is provided at the 45 rear wall 66' of die hole 66, with a forwardly projecting die portion 130 having forwardly converging vertical side walls 131 terminating in transversely extending shoulders 132, and a forward extension 133 50 is provided between these shoulders, having forwardly converging vertical side walls 134 forming a wedge shaped die portion corresponding in outline to the point to be formed at the front of the fastener, the apex 55 of this wedge shaped die portion being directly rearward from the apex of the V-shaped notch 68 in the front wall of the die hole, and spaced therefrom a distance corresponding to the width of the fastener 60 from front to back. This projection 130 may be formed on the replaceable member 73. The main punch 70 is formed with two punch portions 136 each formed at its outer face to fit the side walls of the die hole 66 65 and each provided with an inner wall por-

tion 137 extending obliquely inward and forward so as to slide past and conform to the forwardly converging side wall portions 131 of the die projection 130. A web portion 138 connects the main punch member 70 with a forward prong bender 139 formed as a flange on said web and fitting against the front and side walls of the way 63 and of the die hole 66. The vertical channel or way 72 for guiding the punch 71 is formed 75 by the front wall of punch 70, rear wall of part 139, the web portion 138 connecting side walls and the inner face of the removable side plate 64 of the die head. The punch 71 is provided in its rear face with 80 a vertical V-groove 135 adapted to co-operate with the wedge-shaped die portion 134, and with a transversely extending wall 74 at each side of said groove.

The operation is as follows:

85 A stack of shade cloths indicated at 127 in Fig. 2, cut to the proper length and width is placed on the table 1, the front edge of said cloths being brought into proper parallelism with the roller support by abutment of one side against the shade gage 126. The die mechanism carried by arm 55 is moved far enough to one side by means of handle 77 to be out of the way and a shade roller indicated at 128 in Fig. 9 is placed 90 on the roller support 39 so that the end containing the spring engages chuck 22, said support having been previously adjusted as above described so that the pin at this end of the roller will enter the recess in chuck 22. 100 The top shade cloth is then drawn forward over the inclined platform 125 until its forward edge portion is over the center of the roller in position for mounting, the said platform enabling the shade to lie flat on 105 the roller. Then the die mechanism is moved by handle 77 to position for driving the first staple, the lever 75 being held at such elevation as to hold the key 56 in the sleeve 53 out of engagement with both the upper 110 and lower edges of the groove 57 in shaft 54 so that the arm 55 and the die means carried thereby may be readily moved to the required position. Handle 77 is then lowered 115 until the bottom plate 65 of the die head strikes the shade roller, the concave portion 65' of such head then resting on the roller and arresting further downward movement of the die head, and also holding the roller firmly for the fastening operation. The die 120 operating parts then occupy the position shown in Fig. 3, lever 75 being in its most elevated position relatively to the die head, so that both the punches 70 and 71 are in the most elevated position. Assuming that 125 the machine is in normal operation, the staple strip 100 extends forwardly from reel 101 through feeding device 108 and retaining device 110 and through channel 39 in the bottom member 65 of the die means, and 130

over the die projection 130 at the rear of the die hole 66, the forward end of the strip which is pointed as shown at 142 from the last operation, being in engagement with 5 the front wall of the die hole, in such manner that the point or prong 142 enters notch 68 in said front wall and thereby accurately centers the strip and at the same time arrests the strip in proper position for cutting off 10 of the next staple. The downward movement of the lever 75 being continued, it moves the punch 70 downward through the action of bent links 78, bell crank 81, links 85, lever 87 and links 90, and at the same 15 time it moves the punch 71 downward directly through the action of links 96. When said punches have been moved sufficiently in this operation to bring them into contact with the staple strip, the die parts occupy 20 the positions shown in Fig. 4. As both the main punch portions 136 are rounded at bottom as shown at 70', they touch the staple strip only at their rear edges, and the inner faces of these punch portions diverge 25 rearwardly and extend beyond the edges of the staple strip, so that they cut the strip by a shearing cut beginning at each side and cutting obliquely inward and forward toward the middle of the strip, thus forming 30 prongs indicated at 141 in Fig. 18, which are widest at their forward portions and taper to sharp points at their rear ends. The oblique curvature of the bottom faces 70' of the punch portions 136 also starts the bending 35 down or forming action on the prongs so cut, this action being completed by the vertical front faces of said punch portions, as they pass on down through the strip, thereby bringing said prongs to vertical position 40 as shown in Figs. 5 and 18. At the same time the prong bender 139 at the front of the main punch 70 engages the point or tip 142 at the forward end of the staple strip and bends it down to form a vertical 45 prong, as shown in Fig. 5, the forward extension 133 of the female die serving as a support for the part of the strip directly at the rear of this tip portion, during this operation. By this time the lower arm of 50 bell crank 78 has moved nearly to dead center position with respect to the pivotal connections of links 85 with the said bell crank and with the lever 87, so that further downward movement of lever 75 produces only 55 a slight further movement of the main die or punch 70. During the above described operation the severing punch 71 has been brought to position with its lower face just above the staple strip, as indicated in Fig. 60 5. Continued downward movement of lever 75 causes the punch 71 to move on downward, with the result that the transversely extending walls 74 of the said punch will cooperate with the transversely extending 65 shoulders 132 of the forward projection 120

of the female die so as to cut the strip transversely, these cuts indicated at 144 in Fig. 14 extending inwardly from the forward ends of the oblique cuts 145 made by the main punch portions and the obliquely extending walls of the V-groove 135 in the punch 70 then coöperating with the corresponding side walls 134 of the forward extension 133 of the die projection 130 to cut the strip, as indicated at 146 obliquely inward and forward to form the point 142 for the next staple and also to sever the staple just formed, these cuts by reason of the oblique curvature of the bottom of punch 70, being also draw or shear cuts, beginning at 75 the transverse cuts and ending at the extreme point of the staple. While the punch 71 is thus cutting a point at that part of the strip between the walls of the vertical groove, the parts of said punch at each side 80 of said groove are pressing the side portions 147 of the staple already cut, somewhat downward, and in the further downward movement of punch 71, these side portions of said punch act to drive the severed staple 85 downward so that the prongs 141, 142 thereof are driven into the shade roller as shown in Fig. 9. As the staple is thus driven home, the main punch portions follow down somewhat as shown in said figure, so that the 90 downwardly extending prongs 141, 142 are laterally supported while they are being driven. The forwardly extending wedge shaped die portion 133 also aids in guiding and supporting the staple laterally in this 95 driving operation by engagement in the notch 148 formed in the rear of the staple. The fact that the bottom of the driving punch 70 is approximately of the same 100 curvature as the surface of the shade roller enables the staple to be conformed to such surface and to give a neater finish to the work as well as a more secure hold for the 105 cloth.

When a staple has been formed and driven 110 in this manner the hand lever 75 is raised, and when the upward movement of the arm 55 is arrested by engagement of key 56 with upper edge of groove 57, the continued upward movement of lever 75 causes the 115 punches 70 and 71 to move upward to strip the dies, the strip 100 being held down by the pin 149. The die mechanism is then moved to position for inserting the next 120 fastener and the operation is repeated. When the part of the shade roller is reached adjacent to the winding spring for the shade, the pin or projection 60 engages the fixed stop 61 to arrest the downward movement of the die head, and thereby prevent excessive 125 pressure on the shade roller at this part, which is weakened by the bore made for said spring. In the downward movement of lever 75 it strikes projection 112 on lever 108 and moves the gripping means 116 back, 130

said means slipping over strip 100 in this movement. As lever 75 is moved upward, spring 113 restores lever 108 to normal position causing gripping means 116 to feed strip 100 forward until the point 13 engages notch 68 in the front wall of the die hole, thereby bringing the strip to position for cutting and driving the next staple. It will be noted that but one feeding operation is necessary, the staple being wholly cut while the strip is in one position, and being then driven without requiring further advance of the strip.

The staple or fastener made by the operation above described is shown in Figs. 16 to 18 and comprises a downturned front prong, point or tip 142, two rearwardly diverging side portions or arms 147, united at their forward ends by said front prong, and a downturned prong 141 at the rear end of each of said side portions. Each of said side portions is curved so as to be concave on the bottom.

This curvature of the top of the staple is due primarily to the bending down of the forward part of the staple strip, by the action of the punch or prong bender 139, the downward inclination of the top face of the projection 66' of the die member 73, permitting this bending, and the curvature of the bottom faces of punch 71 maintaining and completing the bend so formed in the staple top.

When all the staples required for fastening the shade to the roller have been driven in the manner above described, the handle 15 is moved to the left, so as to cause pick-up 19 to engage one end of the shade roller and causes the latter to be gripped between pick-up 19 and chuck 22 and handle 15 is then operated to turn the pick-up shaft 11 and thereby raise chuck 22 and pick-up 19 so as to lift the shade roller off the support 39 and at the same time cause the pulley 27 to engage belt 28 so as to tighten said belt and cause it to rotate the pulley 27 and the chuck 22 connected thereto. The shade roller is thereby rotated so as to wind the shade thereon, the operator pressing the shade with one hand so as to cause it to wind tightly on the roller. Handle 15 is then moved to the right so as to release the shade roller from the pick-up device 19, and the shade roller with the shade wound thereon is then removed from the machine which is then ready to receive another roller.

Inasmuch as the die means moves in an arc around shaft 54, it is necessary to always bring the top of the roller to a certain position, irrespective of the size of the roller, so that it may be in position to properly engage the bottom of the die means and to receive the staple when driven thereby. To adapt the device for any of the usual sizes of rollers, the roller support is adjusted vertically

when necessary, by operation of lever 44, causing wedges 40 to ride on studs 41, and the adjustment is determined by engagement of slot 48 in said lever with the proper one of the fixed studs 49. Other means for gag- 70 ing the adjusting movement of the lever for bringing the roller support to proper vertical position may however be used, for example, as shown in Fig. 21, wedges 150 having a series of recesses or notches 151, may 75 be provided in place of the smooth wedges 40, being adapted to engage studs 41 and support the roller support 39 in any one of several positions. In this case the gaging means described above for lever 44 may be 80 dispensed with, the number and arrangement of the recesses 151 corresponding to the number and arrangement of the studs 49 in the former case.

In case a more accurate and flexible means 85 of adjustment for the roller support is desired, lever 44 may be provided with a downward projection 152 engaging a series of ratchet teeth 153 on a segment 154 corresponding to the segment 50 in the first-de- 90 scribed case. In this case the position of lever 44 must be determined by experiment for each size roller, but on the other hand a wider range of adjustment is provided for.

The shade winding mechanism herein dis- 95 closed is not claimed herein, as it forms the subject matter of my divisional application, Ser. No. 154163, filed Mar. 12, 1917, and the particular form of staple herein shown is claimed in my application, Ser. No. 154162, 100 filed Mar. 12, 1917, the same being a division of this application.

What I claim is:

1. In a shade mounter, a roller supporting bed, fastener driving means mounted to move 105 longitudinally with respect to the roller when the latter is on said roller supporting bed, said fastener driving means being mounted to swing in a vertical plane, and operating handle means for moving said fastener driving means longitudinally with respect to the roller and for operating said fastener driving means vertically to drive a fastener into the roller.

2. In a shade mounter, a horizontally ex- 115 tends roller supporting bed, a shaft ex- tends parallel to said bed, an arm mounted to slide horizontally and to turn vertically on said shaft, fastener driving means carried by said arm and an operating handle pivot- 120 ally connected to said arm and having an operating connection with said fastener driv- ing means so that by moving said handle horizontally, the arm may be moved longitudinally on said shaft and by moving said handle vertically the arm may be swung vertically on said shaft to bring the fastener driving means down onto the roller on the said supporting bed and by further vertical movement of said operating handle, the fas- 125 130

tener driving means may be operated to drive the fastener into the roller.

3. In a shade mounter, a table, a horizontal shaft, mounted in fixed position above said table, an arm mounted to slide horizontally and to turn vertically on said shaft, fastening means carried by said arm, guide means on said table extending parallel to said shaft, a roller supporting bed mounted 10 to slide vertically in said guide means, and provided with wedges, fixed means on said guide means for engagement by said wedges to raise the said bed, and means connected to said bed to move the same longitudinally and 15 thereby adjust it vertically.

4. In a shade mounter, a shade roller support, a fixed shaft extending parallel to the shade roller when on said support, an arm mounted to slide longitudinally and to turn 20 vertically on said shaft, a die head carried by said arm and provided with means for engaging a shade roller to limit the downward movement of the die head, fastener forming and driving means mounted in said 25 die head, and a lever pivoted on said arm and connected to the fastener forming and driving means and provided with an operating handle to operate the fastener forming and driving means in rotative movement of 30 said lever on said arm, said lever and arm being so connected by said fastener forming and driving means as to enable the lever to turn the arm on said shaft, and said lever also serving for longitudinal operation of 35 said arm on said shaft.

5. In a shade mounter, a shade roller support, a fixed shaft extending parallel to the shade roller when on said support, an arm mounted to slide longitudinally and to turn 40 vertically on said shaft, a die head carried by said arm and provided with means for engaging the shade roller to limit the downward movement of said arm, and with means for limiting its downward movement, in certain longitudinal positions of the arm on the 45 shaft, independently of the shade roller, die means mounted in said head, and a lever mounted on said arm to have a limited pivotal movement thereon for operation of the 50 die means, said lever also serving for turning the arm on the shaft and for longitudinal movement of the arm on the shaft.

6. In a shade mounter, a shade roller support, a fixed shaft extending parallel to said 55 support, an arm mounted to slide on said

shaft and to have a limited rotative movement thereon, die means mounted on said arm and adapted to form and drive staples, a lever pivotally mounted on said arm and connected to said die means to operate the 60 same, a staple strip reel mounted on said arm, strip feeding means mounted on said arm and operated by said lever to feed the strip from the reel to the die means, and a spring connecting said feeding means to the 65 arm to restore the feeding means to normal position.

7. A staple forming means comprising a female die having a die hole whose rear wall is formed with a projection having forwardly converging side walls, shoulders at the forward ends of said walls and wedge extension with forwardly converging side walls in front of said shoulders, channel means for guiding a strip over said projection, a punch mounted to slide toward and from said female die, and having portions adapted to enter said die hole at each side of said projection to cut prongs and to bend the same down, and said punch being provided with a vertical way and with an extension in front of said way to engage and bend down the pointed end of the staple strip cut by a preceding operation, and a severing punch mounted to slide in said way in the 80 first named punch and having a notch conforming to the wedge extension on the female die, and coöperating therewith to sever and drive the formed staple and cut the front prong for the next staple, by one movement.

8. In a staple forming and driving means, means for feeding a staple strip, die means for cutting the strip obliquely inward at each side, and for bending down the portions 95 so cut to form prongs, die means adapted to operate subsequently to the first named die means for cutting inwardly and forwardly from the first cuts to sever the staple and to form a forward point prong for the succeeding staple, and die means operating simultaneously with the first named die means to bend down the forward prong formed in the preceding operation of the second named die means.

In testimony whereof I have hereunto set my hand, at Los Angeles, California, this 25th day of September, 1916.

LOUIS B. GIRARD.
